HUBERT F. KRANTZ, OF BROOKLYN, NEW YORK, ASSIGNOR TO KRANTZ MANUFACTURING COMPANY, INC., OF BROOKLYN, NEW YORK, A CORPORATION OF NEW YORK.

SUPPORTING-BRACKET FOR SWITCH MECHANISM.

1,399,497.

Specification of Letters Patent. Patented Dec. 6, 1921.

Application filed August 5, 1918. Serial No. 248,328.

To all whom it may concern:

Be it known that I, HUBERT F. KRANTZ, residing at Brooklyn, in the county of Kings and State of New York, have invented certain new and useful Improvements in Supporting-Brackets for Switch Mechanism, of which the following is a specification.

This invention relates to a supporting bracket for switch mechanism such as that shown in my co-pending application Serial No. 208,797, filed December 26, 1917.

The supporting bracket shown and described in the present application is designed particularly as an improvement upon the supporting bracket shown and described in said co-pending application.

An object of the present improvement is to provide a supporting bracket which may be more cheaply and easily manufactured and which will serve its purpose of properly spacing certain elements of the switch mechanism with a more uniform accuracy than the supporting bracket over which it is an improvement.

A further object is to provide a supporting bracket which will afford ample protection for parts of the switch mechanism and thereby render it possible to omit a protective member employed in the construction shown in said co-pending application.

A more detailed object is to provide a supporting bracket of the kind indicated made up wholly of a single piece of sheet metal bent and otherwise shaped to provide all of the necessary features thereof.

Other objects and aims of the invention, more or less specific than those referred to above, will be in part obvious and in part pointed out in the course of the following description of the elements, combinations, arrangements of parts and applications of principles, constituting the invention, and the scope of protection contemplated will be indicated in the appended claims.

In the accompanying drawings which are to be taken as a part of this specification, and in which I have shown merely a preferred form of embodiment of the invention:

Figure 1 is a side elevational view of a bracket constructed in accordance with this invention, and diagrammatically representing the same in association with certain of the parts to which it is connected.

Fig. 2 is an upper edge view of the bracket shown in Fig. 1, and also illustrating diagrammatically certain of the parts with which it is connected as said parts are seen from above, and

60

Fig. 3 is a front edge view of the bracket, this is also diagrammatically representing certain of the parts with which the bracket is connected.

In order to render the purpose of the present improvement more clearly apparent, it may be stated that the switch device shown in the above mentioned co-pending application includes a pair of switch blades in a position between two walls so that the switch blades are guarded and protected by said walls. The switch blades are pivoted at their mid-portions and are adapted to swing their opposite ends into and out of engagement with stationary contacts carried by the two walls respectively. Access may be had to the space between the walls only by removing one of the walls.

The successful operation of such a device, of course, depends upon the proper positioning of the stationary contacts relative to the swinging blades. Where the blades are intended to swing for making contact at different times relative to each other, the necessity for accuracy in the positioning of the contacts, as is the case in said co-pending application, is more evident.

The structure shown in said co-pending application includes a supporting bracket for the blades and for the two walls, but this bracket is made up of a plurality of separately formed elements connected together by rivets or the like. It has been found, however, in practice in manufacturing a large quantity of the devices, that the component parts of the supporting brackets are seldom assembled with the degree of accuracy necessary to insure proper positioning of the walls and the switch blades when said walls and blades are connected to the supporting bracket.

The present device entirely over-comes this difficulty since, by reason of its being a single piece of pressed metal, any number of similar pieces identically shaped may be made from the same dies.

Referring to the drawings for describing in detail the structure which is illustrated therein, the reference character L indicates the supporting bracket. The reference char-

110

acter G indicates one of the walls. This may be referred to as the rear, or supporting wall. The reference character H indicates the second wall which may be referred to 5 as the front, or guard wall. These parts are all contained within a casing 1 having a door 2 at its front side spaced from the wall H to provide a compartment in front of said wall H suitable for containing 10 fuses, or the like, accessible when the door is open. The switch blades are indicated at 3 and 4, said blades being serviceable as starting and running blades respectively as for use in motor controlling.

15 The blades 3 and 4 are positioned between the walls G and H and are carried in suitable carriers 5 which extend across the space between said walls, being substantially parallel with said walls, and being pivotally supported at their opposite ends in supporting brackets at least one of said brackets, as L, being constructed in the manner now to be described in detail.

25 The supporting bracket L is made up of a single elongated piece of sheet metal positioned to extend between the walls G and H. A right angularly disposed flange 6 is formed at its rear edge, said flange lying flat against the wall G and being connected thereto by suitable bolts, or rivets 7.

30 The wall G is fixed rigidly within the casing, as by means of bolts 8, and serves as a permanent support for the bracket L.

35 At its upper and lower ends the piece of sheet metal is formed with short extensions 9 and 10, and each of said extensions is provided with a right angularly disposed flange 11 at its rear edge, the two flanges 11 being in alignment with each other and in a 40 plane parallel with the flange 6. These flanges 11 serve for the attachment of the front wall H, said front wall being connected thereto by suitable screws, or bolts 12 which enter suitably threaded holes 13 formed through the flanges. The bearing apertures, 45 as 14, for receiving the adjacent ends of the carriers 5 are formed through the intermediate or body portion of the piece of sheet metal in a proper position between the planes 50 of the flanges 6 and 11.

55 Since all of the brackets are made by a given set of dies, the flanges 6 and 11 are uniformly spaced and the apertures 14 also uniformly spaced with respect to said flanges. It necessarily follows that the walls, to be connected with said flanges, will all stand correctly to coöperate with the switches supported in said apertures.

60 A further aperture 15 is provided spaced from the upper aperture 14 adapted to support the stationary end of the toggle for operating the upper carrier 5, and an arcuate slot 16 is likewise provided to limit the movements of the toggle. An aperture 17 is provided for supporting an anti-friction roller

18 against which the operating element 19, for the lower carrier 5, may engage.

65 The apertures 15, 16 and 17, being formed in the same piece of material as the apertures 14, and being formed at the same time, of course, said apertures 15, 16 and 17 are always correctly positioned with regard to the apertures 14.

70 The front portion of the piece of sheet metal projects forwardly beyond the plane of the flanges 11, and the forward edge is provided with a right angularly disposed flange 20. This flange 20 serves as a guard member beyond the forward face of the wall H. The wall H attached to the flanges 11, is necessarily positioned with its edge, as 21, spaced away from the main, or body part 22 of the bracket so as to accommodate the switch operating mechanism 23 therebetween as most clearly seen in Fig. 2, and the flange 20 serves as a guard to prevent the accidental insertion of a tool or the like into engagement with the switch blades or other parts, through the opening between the surface 75 21 and the part 22 of the bracket.

75 The flanges 11 may be extended beyond the flanges 6 and 20 so as better to facilitate the provision of the space between the parts 21 and 22. If necessary the flange 20 may be formed with a suitable opening 24 there-through for accommodating a protruding portion of the switch operating mechanism.

80 It will be noted that each of the flanges 6, 11 and 20 above described, all project in the same direction upon the bracket, hence 85 they may be all formed by a single operation.

85 If found necessary, a reinforcing bracket 95 may be positioned to furnish additional support for the pivot shaft of the roller 18.

90 While, as above suggested, the bracket L 100 is supported by the wall G and in turn supports the wall H, it is apparent, however, that this invention is not limited to this specific detail as the essential characteristic of the invention resides in the fact that the bracket L supports both of the walls in a 105 given relation to each other and to the switch blade between them.

95 As many changes could be made in this construction without departing from the 110 scope of the invention as defined in the following claims, it is intended that all matter contained in the above description or shown in the accompanying drawings, shall be interpreted as illustrative only and not in a 115 limiting sense.

Having thus described my invention, what I claim as new and desire to secure by Letters Patent is:—

1. In a switch mechanism comprising a 120 pair of walls spaced apart, a contact supported by one of said walls, and a switch blade intermediate said walls movable into and out of engagement with said contact, the combination therewith of a supporting 125 roller 130

- bracket for said switch blade and said two walls, said supporting bracket comprising a single piece of material shaped to provide attaching means for each of said elements 5 and having a laterally projecting flange formed thereon serving as a guard member for said switch blade.
2. In a switch mechanism comprising a pair of walls spaced apart, a contact supported by one of said walls, and a switch blade intermediate said walls movable into and out of engagement with said contact, the combination therewith of a supporting bracket for said switch blade and said two walls, said supporting bracket comprising a single piece of material bent to provide parallel flanges thereon spaced apart and adapted to be connected with said walls, and said piece of material having a portion extending 15 beyond the space between said flanges constituting a guard member for said switch blade.
3. In a switch mechanism comprising a pair of walls spaced apart, a contact supported by one of said walls, and a switch blade intermediate said walls movable into and out of engagement with said contact, the combination therewith of a supporting bracket for said switch blade and said two walls, said supporting bracket comprising a single piece of material bent to provide parallel flanges thereon spaced apart and adapted to be connected with said walls, and said piece of material having a further 20 flange formed thereon constituting a guard member for said switch blade.
4. In a switch mechanism comprising a pair of walls spaced apart, a contact supported by one of said walls, and a switch blade intermediate said walls movable into and out of engagement with said contact, the combination therewith of a supporting bracket for said switch blade and said two walls, said supporting bracket comprising a single piece of material bent to provide parallel flanges thereon spaced apart and adapted to be connected with said walls, and said piece of material having a portion extending 25 beyond the space between said flanges 30 and provided with a further flange substantially parallel with said first flanges adapted to constitute a guard member.
5. In a switch mechanism comprising a pair of walls spaced apart, a contact supported by one of said walls, and a switch blade intermediate said walls movable into and out of engagement with said contact, the combination therewith of a supporting bracket for said switch blade and said two walls, said supporting bracket comprising a single piece of material having a plurality of flanges formed thereon, certain of said flanges having means for the attachment of said walls, and another of said flanges constituting guard means for the switch blade. 35
6. In a switch mechanism comprising a pair of walls spaced apart, a contact supported by one of said walls, and a switch blade intermediate said walls movable into and out of engagement with said contact, the combination therewith of a supporting bracket for said switch blade and said two walls, said supporting bracket comprising a single piece of material having a plurality of flanges formed thereon all projecting 40 in a common direction and being substantially parallel to each other, certain of said flanges having means for the attachment of said walls, and another of said flanges constituting guard means for the switch blade. 45
7. In a switch mechanism comprising a pair of walls spaced apart, a contact supported by one of said walls, and a switch blade intermediate said walls movable into and out of engagement with said contact, the combination therewith of a supporting bracket for said switch blade and said two walls, said supporting bracket comprising a single piece of material having a pair of flanges formed thereon for supporting said 50 two walls, one of said flanges being extended to support its respective wall in a position with said wall spaced from the main portion of said piece of material so as to provide a space to accommodate operating means 55 for the switch blade, and said piece of material having a further flange formed thereon disposed to constitute a guard member with respect to said space.
- In testimony whereof I affix my signature 60 in the presence of two witnesses.
